UNITED STATES PATENT OFFICE.

WILLIAM ROBERT SANDERS, OF CHICAGO, ILLINOIS, ASSIGNOR TO WESTERN ELECTRIC COMPANY, INCORPORATED, OF NEW YORK, N. Y., A CORPORATION OF NEW YORK.

ABRADING APPARATUS.

Application filed October 7, 1924. Serial No. 742,110.

This invention relates to an abrading apparatus, and more particularly to an improved apparatus for abrading the surfaces of articles preliminary to the application of

should be understood, however, that the present invention is capable of other applications and the novel features thereof should be limited only by the scope of the appended claims.

- 5 a protective coating thereon.

The object of this invention is to provide an improved method of and mechanism for supplying an abrading material to an abrading apparatus.

10 Other objects and advantages will become apparent in the following detailed description, and the novel features of the invention will be particularly pointed out in the appended claims.

15 The preferred embodiment of the invention comprises a sand blasting apparatus having a treating chamber within which one or more blast nozzles are caused to direct sand or other abrading material upon the 20 surfaces of the articles contained therein. The used or spent sand leaves the treating chamber through apertures in the walls thereof and is collected in a receptacle suitably positioned below the treating chamber.

25 Both the receptacle and the treating chamber are inclosed in a cabinet which is provided with a movable dump door through which the treated articles are ejected and collected in a suitable container positioned 30 nearby. The spent sand receptacle is connected with an independent supply source so that the sand consumed in the abrading operation by conversion into dust and withdrawn by the exhaust system is constantly 35 replaced, thereby maintaining the sand in the receptacle at a substantially constant level. The dump door is positioned above the sand level in the spent sand receptacle, thereby preventing the escape of sand when 40 the door is opened.

One embodiment of the invention is illustrated in the accompanying drawings, in which

Fig. 1 is a front elevation, partly in section, of a sand blast apparatus embodying the features of the present invention;

45 Fig. 2 is a vertical section on the line 2—2 of Fig. 1, and

Fig. 3 is a vertical section on the line 3—3 of Fig. 2.

The invention as herein illustrated and described is particularly adapted to an abrading apparatus, such as disclosed in the copending application of Robert Roscoe, Serial No. 742,114, filed October 7, 1924. It

claims.

Referring now to the drawings in detail wherein like reference characters designate corresponding parts throughout the several views, 10 is a sheet steel cabinet within which are inclosed all of the operating parts of the machine. A sand hopper comprising two conical shaped receptacles 11 is suitably supported near the bottom of the cabinet 10, and sand from a supply source 14 is introduced into each receptacle 11 through an inlet pipe 12, which at its point of connection to the side of the receptacle 11, is disposed at an angle of approximately 45° whereby the sand in the receptacle is maintained at a substantially constant level as indicated by the dotted line A, Fig. 3. The bottom or reduced portion of each receptacle 11 is open and is connected with a housing or sand supply fixture 13.

Rotatably supported in the upper part of the cabinet 10 is a barrel shaped chamber 15 comprising a perforated cylindrical portion 16 and end portions 17 and 18. A removable door 19 forms a part of the cylindrical portion 16 and is provided with a suitable cam latch 20 by which it is securely locked in position. Sand blast nozzles 22 project into the chamber 15 through openings 23 in the end portions 17 and 18 thereof. Each sand blast nozzle 22 is connected to a chambered fixture 24 which carries therein an air nozzle 25 which extends a short distance into the sand blast nozzle 22 to give the correct siphoning effect. The sand supply fixture 13 is connected with the fixture 24 by a pipe 21 which, at the point of connection with the sand supply fixture 13, is disposed at an angle of approximately 45°, and through which the sand is drawn therefrom to the sand blast nozzle 22. An air agitator nozzle 27 is located within the fixture 13 and serves to keep the sand therein in a suitable condition to be drawn, and also assists in moving the sand therefrom through the pipe 21 to the sand blast nozzle 22. An air supply line 29 is connected with the air nozzle 25 in the fixture 24 and with the air agitator nozzle 27 in the sand supply fixture 13. A water separator 26 of any well known construction is provided in the air line 29.

for removing the water therefrom and a suitable pipe or conduit 28 is provided for draining off the water removed thereby. An air nozzle 30, independent of the air nozzle 25, projects into the chamber 15 through the opening 23, and air flowing therethrough serves to remove the dust and pulverized sand from the surfaces of the treated articles before they are removed from the treating chamber. A three way valve 32, provided with an operating lever 33, is connected with the main air line 29 for controlling the air supply to the air nozzles 29 and 30 and to the air agitator nozzle 27.

The treating chamber 15 is supported on a pair of idler rollers 39 and a pair of friction drive rollers 40. The idler rollers 39 are keyed to an idler shaft 41 rotatably journaled in bearings 42, and the friction drive rollers 40 are keyed to a shaft 43 rotatably journaled in bearings 44. A sprocket 45 is keyed to the end of the shaft 43 and is driven by a chain 46 from a sprocket 47 secured to a main drive shaft 48. The shaft 48 may be driven from any suitable source of power, such as an electric motor 49, and a gear reducer of a well known type indicated generally at 50, may be employed to operate the machine at the required speed. The sprockets 45 and 47 and the chain 46 are inclosed in a housing 51 secured to the frame 10.

To facilitate introducing articles to be treated into the chamber 15, a tray or loading platform 55 is provided which is hinged at 56 to the frame 10 so that it may be moved to the position wherein it is shown in dotted lines in Fig. 2, when the door 19 is removed from the chamber 15. The construction and operation of the loading platform 55 is fully described in the above mentioned copending application, and since it forms no part of this invention it is thought that a further detailed description thereof is unnecessary.

Suitably supported directly below the treating chamber 15, and disposed at an angle of approximately 45° is a perforated steel plate 60, which is in alignment with a dump chute 61 secured to the frame 10. A dump door 62 is hinged at 63 to the frame 10 and opens inwardly to provide an unrestricted passage for the ejected articles between the plate 60 and the chute 61. The dump door 62 is positioned above the sand level in the spent sand receptacle 11 thereby preventing the escape of sand when the door is open. A lever 64 for operating the dump door 62 is positioned at the side of the cabinet 10, within convenient reach of the operator. A rubber sheet 65, secured to the inner side of the dump door 62, serves to prevent the escape of sand from the cabinet 10.

The cabinet 10 is topped by an exhaust cowl or canopy 70 which is secured to the cabinet and to exhaust pipes 71 by eye bolts

72 so that it can be quickly disconnected and removed when it is necessary to replace or repair the treating chamber 15. The sand which is converted into a pulverized condition by the abrading process is withdrawn through the exhaust. A door 74 is provided on the front side of the cabinet 10 and is adapted to be elevated in suitable guideways to expose the treating chamber 15 during the loading and unloading operations. The door 74 is suspended by cables 75 threaded over pulleys 76 supported by a horizontal I-beam 77 and connected to balancing weights 78 to facilitate the opening and closing thereof.

The spent sand escapes through apertures 80 in the treating chamber 15 and re-enters the receptacle 11 through a steel screen 81, covering the top opening thereof. The sand level in the receptacle 11 is maintained substantially constant, since the sand consumed in the abrading operation is constantly replaced through the conduit 12 leading from the supply source 14. It is apparent that sand will continue to flow by gravity from the supply source 14 into the receptacle 11 until the sand level therein reaches the top of the opening in the conduit 12, as clearly indicated in Fig. 3.

What is claimed is:

1. In an abrading apparatus, a treating chamber for housing an article to be treated, a cabinet inclosing said chamber having an opening therein through which the treated article is ejected therefrom, a hopper exterior to one side of the cabinet containing a supply of abrading material, means for conveying the material from said hopper into the treating chamber, and a receptacle communicating with said hopper and mounted within said cabinet for collecting the spent abrading material, said hopper being in continuous communication with the receptacle for maintaining the abrading material in said receptacle at a substantially constant level below the opening in said cabinet.

2. In an abrading apparatus, an inclosed cabinet having an opening, a treating chamber housed by the cabinet containing an article to be treated, a receptacle for collecting the spent abrading material from said treating chamber, a storage hopper in communication with said receptacle for continuously supplying material thereto, a movable door closing an opening in the cabinet in one position through which the treated article is ejected therefrom and movable to another position whereby it closes the opening into said receptacle to which the spent material passes.

3. In an abrading apparatus, an inclosed cabinet having an opening, a rotary treating chamber housed therein containing an article to be abraded, a receptacle for collecting the spent abrading material from the treating

chamber, a storage hopper in communication with the receptacle for continuously supplying abrading material, and a door positioned below the treating chamber closing in one position the opening in the cabinet through which the treated article is ejected and movable to another position whereby it closes

the opening into said receptacle to which the spent abrading material passes.

In witness whereof, I hereunto subscribe my name this 26 day of September, A. D. 1924.

WILLIAM ROBERT SANDERS.
